(57) **CLAIM**

The ornamental design for light sources arranged in a pattern, as shown and described for at least one of the first or second embodiments.

DESCRIPTION

FIG. 1 is a front perspective view of light sources arranged in a pattern, showing a first embodiment of our new design; FIG. 2 is a front view of the light sources arranged in the pattern according to the first embodiment; and, FIG. 3 is a back view of the light sources arranged in the pattern according to the first embodiment; and, FIG. 4 is a top view of the light sources arranged in the pattern according to the first embodiment. Bottom, left-side, and right-side views of the first embodiment are each the same as the top view in FIG. 4. The portions of the images shown with broken lines are for illustrative purposes only and form no part of the claimed design.
